(57) **CLAIM**

The ornamental design for a bell music instrument for whirl sound effect, as shown and described.

DESCRIPTION

FIG. 1 is a side view of a bell music instrument for whirl sound effect in accordance with my design;

FIG. 2 is a front and side perspective view of the bell music instrument for whirl sound effect of FIG. 1;

FIG. 3 is a side and rear perspective view of the bell music instrument for whirl sound effect of FIG. 1 that further includes a rope connected to the bell; and,

FIG. 4 is a front and side perspective view of the bell music instrument for whirl sound effect of FIG. 1; opposite the side shown in FIG. 2.

The broken lines in the drawing views are included for the purpose of illustrating portions of the bell music instrument that form no part of the claimed design.

1 Claim, 4 Drawing Sheets
